INVENTOR

UNITED STATES PATENT OFFICE

JOHN F. BLYTH, OF EAST ORANGE, NEW JERSEY, ASSIGNOR TO ELLIS-FOSTER COMPANY, OF MONTCLAIR, NEW JERSEY, A CORPORATION OF NEW JERSEY

CONTAINER AND CAP THEREFOR

Application filed July 9, 1927. Serial No. 204,436.

This invention relates to containers and especially to those adapted for containing liquid foods such as milk and is concerned especially with glass containers such as milk bottles covered and protected by a paper covering in box-like form held in place over the bottle mouth by friction, by crimping, or by other means.

It has been proposed to press or draw paper into cap-like form, or what is known as the ramekin shape, that is, the sides or skirt of the cap being folded or plaited. Caps of this type are usually impregnated with wax to render water resistant. The grade of paper employed for the purpose is fairly thick in order to secure sufficient strength for handling and this thick and rather stiff paper does not lend itself readily to crimping. Even when impregnated with a hard wax such as carnauba wax, heated and crimped over the bottle mouth a firm closure is not easily secured and furthermore, when exposed to moisture, to which, of course, milk bottles must be frequently subjected over long periods, moisture is absorbed slowly into the paper, swelling it sufficiently to cause the bended portions to expand and the cap to unfold to a degree such that it frequently may be readily pulled off the top with only very slight pull, much less than required in picking up the bottle by gripping the mouth with the hand in the usual way.

It is the purpose of this invention to provide a cover, cap or stopper for milk bottles and a complete container comprising bottle and protecting cover free from the objections of unfolding in the presence of moisture which characterizes the ramekin type of hood cap.

By reference to the accompanying drawings my invention will be made clear. In the drawings like reference characters denote like parts. Figures 1, 2, 3 and 4 show that part of the container which specifically concerns the present invention, it being understood that these figures represent milk bottles, but to conserve space the lower part of the bottle, which may be of the regulation type, is not shown. Figures 1, 2, 3 and 4 therefore show a portion of a bottle in elevation, with

the mouth portion in vertical section, the sections being taken along a diameter of the bottle mouth.

In the drawings, A is a bottle having the closing device B, and the lid or cover C—D. The latter preferably is made in two parts, namely; of the disc D and the bended part or side C. Instead of having the side C fluted, as in the case of the ramekin hood cap, the walls C are straight and smooth, like the sides of a pill box. To attach the disc D firmly to the top of the bottle, the side wall C is in-turned at the top, as shown at E, forming a rim extending around the edges of the disc D. This form appears in Figures 1, 2, 3 and 4. The cover thus obtained may be simply forced onto the top of the bottle and held there by friction, or the lower portion of the sides C may be turned under at F to attach the cover more firmly to the bottle. As shown in Fig. 2 the flange of the bottle is rectangular in cross section, instead of being rounded as in Fig. 1, and the cover is folded under the flange to make simply a right angle turn.

In Fig. 3 the bottle flange has a channel or groove H extending around it and the sides C are pressed into this channel to form the fold I. In Fig. 4 the same arrangement exists, but the bottle flange is tapering. It should be noted that the channel H may be omitted from the type of container shown in Fig. 4, and the cover made to fit the taper of the flange. Preferably the cover is slightly smaller so that merely forcing it onto the bottle mouth yields a firm closure.

Without the taper, but with a cover slightly smaller than the bottle mouth shown in Fig. 1, firm pressure on the cover forces it over the rounded flange and it thereupon grips the bottle in a secure manner without the aid of the clamping folds F. The inside side wall C under such circumstances may be coated with material which has slightly tacky qualities. For example, a surfacing of rosin or various other resins of a slightly tacky nature increases the grip at this point and supplements the locking effect of the fold F, and in many cases obviates the employment of this fold and hence eliminates the operation of

folding necessary when the cover is placed on the bottle.

5 The various operations of folding required to obtain the locking effects shown in the drawings may be carried out by means of appropriate apparatus after the cover has been applied to the bottle.

10 While I have shown the closure disc B separate from the cover C—D, it should be understood that in some cases I may employ a cover having a depressed part fitting into the recess just above B and serving as a stopper for the bottle.

15 Various waxes, resins, oils, and the like, may be used for waterproofing the paper material used in the foregoing. In some cases the paper stock may be sized with various waterproofing emulsions, such as a wax dispersion, so that it becomes adequately waterproof for the purpose. In other cases, especially when a waxed paper disc B is used as a separate closing means, the cover need not be made particularly water resistant.

20 The circular portion D may carry on its upper side any suitable emblem or advertising device.

25 Thus my invention relates to containers for milk, cream and similar beverages and foodstuffs comprising the combination of a bottle 30 having a flanged mouth and a paper cover comprising a header-disc (D) and a side member (E) locked thereto, as for example, by folding or swaging one edge over the other to form a lock or seam or inter-locking fold, as the case may be; said side member fitting into close contact with the bottle mouth flange and preferably having substantially straight sides, that is, free from vertical foldings and plaitings, but if desired 35 having inturned or convoluted lower edges or other gripping means such as are illustrated, including the surfacing of the interior of the side walls with a slightly sticky or tacky substance, preferably employing a minimum amount of such coating almost 40 invisible to the naked eye, to obtain additional adhesion or grip. Said container may have an auxiliary stopper or disc closure (B), or the header-disc (D) may have a depressed portion fitting into a recess in the 45 bottle mouth and if desired be held in place by a disc forced into the depressed portion in order to clamp the recessed portion of the header-disc against the inner walls of said 50 recess.

55 What I claim is:—

1. In containers for milk, cream and similar beverages and foodstuffs, the combination of a bottle having flanged mouth 60 and carrying a protective paper cover comprising a header-disc and a side member folded into locking engagement therewith, said side member fitting into close contact with the bottle mouth flange.

65 2. In containers for milk, cream and sim-

ilar beverages and foodstuffs, the combination of a bottle having a flanged mouth and carrying a protective paper cover comprising a header-disc and a side member provided with an inturned edge folded into locking engagement therewith, said side member fitting into close contact with the bottle mouth flange. 70

3. In containers for milk, cream and similar beverages and foodstuffs, the combination of a bottle having a flanged mouth and carrying a protective waterproof paper cover comprising a header-disc and a side member folded into locking engagement therewith, said side member fitting into close contact with the bottle mouth flange, whereby the cover is securely attached to the bottle and does not substantially unfold within a reasonable time in the presence of moisture. 75

4. In containers for milk, cream and similar beverages and foodstuffs, the combination of a bottle having a flanged mouth and carrying a protective paper cover comprising a header-disc and a side member provided with an inturned edge folded into locking engagement therewith, the inturned edge exerting a firm grip against the bottle flange to secure the cover thereon and to prevent substantial unfolding in the presence of moisture. 80
